(57) **CLAIM**

The ornamental design for a massage therapy device, as shown and described.

DESCRIPTION

FIG. 1 is a perspective top view of the massage therapy device.

FIG. 2 is a front view of the massage therapy device, the side and rear views are mirror images.

FIG. 3 is a top view of the massage therapy device.

FIG. 4 is a bottom view of the massage therapy device.

FIG. 5 is a perspective view of a second embodiment of FIG. 1, the only difference being the inclusion of a base, it being understood that all other aspects of the massage therapy device are the same as those of the first embodiment.

FIG. 6 is a perspective view of the massage therapy device and base, with the device placed downward in the base; and, FIG. 7 is a perspective view of the massage therapy device and base, with the device placed upward in the base.
